BROOM

Milton L. Ballou, R.D.1 Phelps St.,
Gloversville, N.Y. 12078

Filed Nov. 27, 1968, Ser. No. 14,704

Term of patent 14 years

Int. Cl. D7—06; D4—01

U.S. Cl. D49—21

FIG. 1 is a front elevation of a broom showing my new design, the undisclosed rear is a mirror image of the front; FIG. 2 is an end elevational view thereof;

FIG. 3 is a top plan view thereof; and

FIG. 4 is a bottom plan view thereof.

The dominant features of my design resides in the portions shown in full lines, the handle being broken away in FIGS. 1 and 2 to indicate indeterminate length.

I claim:

The ornamental design for a broom, substantially as shown and described.
